COAL DISTRIBUTING APPARATUS FOR
STOKERS

William Thompson Hanna, Cincinnati, Ohio

Application September 26, 1940, Serial No. 358,395

10 Claims. (Cl. 110—105.5)

The present invention pertains to stokers for coal-firing fireboxes of boats and locomotives and more particularly to improved apparatus for distributing coal by fluid blasts directed over the firebox.

In apparatus of this type blasts of steam or other elastic fluid are directed over the firebox and coal moving into the blasts is carried to the different parts of the firebox. Cooperating with a so-called blast chamber, from which the blasts or jets issue, there is a distributor plate below and forward of the jets which coats with them to direct the coal along certain paths. Such distributor plates are usually at least partly within the firebox proper and are subjected to the intense heat of the fire and so normally have a relatively short life and must be readily replaceable. Also, with such apparatus the problem exists of getting desired distribution of coal to the sides and rear back corners of the firebox adjacent the distributing apparatus. This problem is more acute where the firebox is relatively wide and where the firing opening in which the coal distributing apparatus is located is only a relatively short distance above the firebed level.

It is an object of the present invention to provide improved distributing apparatus and to provide improved distributor plate mechanism which is readily replaceable in part or in whole and which is adapted to feed coal to the rear corners of fireboxes of any type so that uniform distribution of the coal in proper proportion to all sections of the firebed may be obtained, with particular attention to the sides and back corners.

Further, since such distributing apparatus is usually located within the firing opening of the firebox it is desirable that the distributing apparatus be constructed for efficient firing without requiring changes in the positioning or size of the firing opening and without obstructing the opening. And it is another object of the present invention to provide improved apparatus which is adapted to fire the sides and the rearward corners without requiring changes in the firing opening even though the firing opening be located relatively a short distance above the firebed and to accomplish this without obstructing the firing opening either for occasional hand-firing or for the entry of boiler repair workmen.

Other objects will be in part obvious and in part pointed out hereinafter.

In the accompanying drawings, in which are shown two embodiments of this invention,

Figure 1 is an axial section through a portion of a conveyor system delivering coal from a ten-

der to distributing apparatus embodying the invention and located in a firing opening in the back wall of a locomotive firebox;

Figure 2 is an enlarged top plan view of the distributing apparatus shown in Figure 1;

Figure 3 is a front elevation of the distributing apparatus of Figure 2 looking at the apparatus from within the firebox;

Figure 4 is a vertical section taken on line 4—4 of Figure 2;

Figure 5 is a top plan of another embodiment of my invention showing certain elevated distributor arms removable from the main distributor plate body;

Figure 6 is a front elevation of the structure shown in Figure 5;

Figure 7 is a side elevation of the structure of Figure 5;

Figure 8 is a vertical section taken on line 8—8 of Figure 5 and showing a blast chamber in cross-section;

Figure 9 shows in perspective a channel arm unhooked and removed from its corresponding supporting section; and

Figure 10 is a top plan of the distributing apparatus of Figure 5 shown located in a firing opening and diagrammatically showing the firebed areas reached by different sections of the distributing apparatus.

Referring to the left side of Figure 1 there is shown in cross-section and numbered 10 a boiler backhead of a locomotive firebox. This backhead has a firing opening 11 and grates 12 at the bottom of the firebox. Encompassing the firing

opening is a coal delivery housing generally indicated at 13 provided with a hand-firing opening 14 aligned with the firing opening 11 and adapted to be covered by the usual fire doors, not shown. The housing 13 is secured to the backhead by bolts, not shown, passing through flanges

extending from the housing, such as flanges 15 and 16. Entering the housing from below is a riser conduit 17 through which coal is delivered into the housing 13 by means of conveyor screws

18 operating in conduit 19 extending from beneath the coal bin on the tender to the riser conduit 17. As the screws rotate coal is continuously removed from beneath the coal bin on the tender and transferred forwardly past a usual crusher to the housing 13 where it may be conditioned and its flow regulated by a pair of oppositely disposed rotating tapered screws 20 and

cause to flow over a delivery ledge 21 as described in my Patent No. 2,044,001, issued June 16, 1936. The coal thus supplied to the housing 13 and

flowing over the ledge 21 is distributed over the firebox by distributing apparatus indicated generally at 22 and comprising a blast chamber generally indicated at 23 and a distributor plate generally indicated at 24. The distributing apparatus distributes the coal by means of steam blasts issuing from the blast chamber and reflected from the distributor plate.

The blast chamber may be of the type described in my Patent No. 2,192,190, issued March 5, 1940, and in the present embodiment comprises, as shown in Figures 2, 3 and 4, a body portion having a top ledge 21a in front of and in the plane of said ledge 21 of the housing 13. The body portion is provided with a high pressure chamber 25 running lengthwise of the body portion and a low pressure chamber 26 (Figure 8) also extending lengthwise of the body portion. Extending forwardly from the high pressure chamber and through fingers 27 forming a grill work are apertures through which the steam flows from the high pressure chamber in the form of high pressure jets. The fingers have a fan arrangement and the tops of the fingers slope downwardly and forwardly so that coal coming from the ledge 21 falls down over the fingers and is screened, the small particles falling down between the fingers and the larger particles riding over the fingers into the path of the high pressure jets which carry such particles to different portions of the firebox. The fine particles are picked up by a sheet jet issuing through an arcuate elongated slot 28 extending across the front of the body portion and connecting with the low pressure chamber 26. The spreading low pressure sheet jet issuing from the arcuate slot 28 carries the finer particles over the different portions of the firebed.

The extreme end fingers 27a are shorter than the others so that coal particles riding down between the fingers 27a and the fingers immediately adjacent tend to fall sidewise into jets issuing from the fingers 27a. This aids in obtaining desired coal feed to the sides of the firebox.

The blast chamber is secured in place in the lower portion of the firing opening against spaced webs 31 extending forwardly from the underside of the housing 13. This is accomplished by securing flanges 29 (extending laterally from the blast chamber) against the forward faces of the webs 31 by means of bolts 30 extending through these flanges and into the webs 31. The front faces of the webs 31 are cut to the proper angle so that when the riser conduit 17 and housing 13 are secured in place with respect to the back-head 10 the jets issuing from the blast chamber have the desired direction.

Steam is supplied to the high pressure chamber through a pipe line 32 entering through the side wall of the housing 13 and connecting to the blast chamber. Likewise the low pressure chamber 26 is supplied with steam from a low pressure line 33.

Referring now to the distributor plate, generally indicated at 24, and looking at Figures 2, 3 and 4, the distributor plate comprises a central table portion 34 which is flat and slopes slightly downwardly and forwardly. Side portions 35 at either side of the table portion are grooved slightly toward their respective ends and diverge to cooperate with the end jets 27a of the high pressure blast and with the low pressure blasts to deliver coal to side portions of the firebox. The plate is located closely adjacent the bottom wall of the firing opening and terminates

5 at its forward end within the firing opening so that it is protected to some extent from the severe heat of the fire.

Integral with the distributor plate and located above the respective side grooves 35 are elevated chutes or channels, generally indicated at 36. The chutes are grooved as indicated by the arrow 37, which grooves gradually become deeper and wider toward their delivery ends. The grooves extend rearwardly to the low pressure jets 38 located at the ends of the blast chamber slightly below its ledge 21a. The chutes extend into the firebox and curve outwardly past the sides of the firing opening.

These chutes cooperate with the low pressure jets 38 to distribute coal over rear corners of the firebox. Because of their elevation and the extent to which they extend into the firebox they satisfactorily reach the rear corners. Whereas for the desired coal distribution it is desirable to 20 screen the coal flowing over the central portion of the ledges 21 and 21a to distribute the larger particles with high pressure jets, such is not necessary for the coal flowing over the extreme side 25 portion of the ledge 21. The coal going over the sides is more homogeneous in size because the larger particles tend to move over the central portion of the ledge 21. Therefore the low pressure jets 38 are satisfactory for handling the coal 30 moving through the chutes 36.

The grooves of the chutes deepening and widening as they do toward their delivery ends take care of the expanding steam jets 38 and serve to offset the possibility of coal catching 35 in and plugging the grooves. The walls 39 of the chutes (forming the inner and forward walls thereof) are increased in thickness toward the delivery end to aid their withstanding the heat of the firebox.

40 These two arms or chutes 36 are integrally supported from the main portion 34 of the distributor plate by upright webs 40 which, as shown in dotted lines in Figure 2, start from the rearward face of the distributor plate, turn at an angle and diverge from each other, forming walls paralleling the channel portions 35. The walls thus formed prevent coal going over the outside of the channel portions 35 where it might fall between the distributing mechanism and the 45 sides of the firing opening and burn.

50 The distributing plate 24 is removably secured to and supported from the blast chamber as follows: Extending forwardly from the extreme side portions of the body portion of the blast chamber 55 are two supporting arms 41 provided at their forward ends with lips 42 extending upwardly.

Extending sidewardly from either side of the distributor plate and in the general plane of the chutes 36 are elongated lugs 43 extending downwardly below the rearward portions of the chutes 36 and extending laterally just beyond the outside edges of the supporting arms 41 on which lugs 43 are adapted to rest. The rearward faces of the lips 42 slope rearwardly and the forward faces of the lugs 43 slope in a similar direction so that as these lugs move into locking position in back of the lips the sloping faces, contacting, 60 force the rearward vertical faces of the chutes 36 against corresponding forward vertical faces 50 of the blast chamber.

65 The distributor plate is aligned with the blast chamber as the two are assembled by shoulders 48 located on the blast chamber outside of fingers 27a. These shoulders guide the inside surfaces

of the vertical webs 40 and so serve to centrally align the distributor plate with the blast chamber. Also the faces 50, turning outward as they do and spaced as they are, serve to center the distributor plate and the blast chamber when the two are thus interengaged.

The distributor plate is prevented from tipping downwardly about the arms 41 and its position with respect to the horizontal is determined by contact between a curved rearward face 47 of the distributor plate and a similarly curved forward face of the blast chamber. These contacting faces both slope rearwardly and serve to lock the distributor plate in engagement with the blast chamber so that it can be unlocked only by tipping the forward end of the distributing plate clockwise as shown in Figure 4.

Referring to Figure 10, as the coal moves over the blast chamber ledge 21a, the coal going over the central portion is screened by the fingers 27 and the larger particles move into the paths of the jets of the fingers and the smaller particles move into the path of the sheet jet as described. The coal is guided by the table portion of the distributor plate over the firebed. This much of the distributing apparatus may be made to cover the areas A, B, C and D as shown in Figure 10. The coal moving over the extreme side portions of the ledge 21a falls into the grooves 37 of the elevated chutes and is carried by the jets 38 to the rear corner portions of the firebox, i. e. areas E and F.

The substantially greater elevation of the chutes 36, which elevation is desirable to enable the jets to reach the corner areas E and F, permits the central portions 34 and 35 of the distributor plate, and indeed the whole blast chamber, to be placed lower in the firing opening than would otherwise be possible. This leaves more room in the firing opening for workmen to enter and overcomes the necessity for enlarged firing openings. Further, by making the channels 36 elevated as they are, it is possible to put more coal into the rear corners. Referring to Figure 3, the amount of coal flowing into these corners may be controlled by means of adjustable slides 49 extending through the sides of the distributor housing 12. As these slides are pushed toward one another they reduce the amount of coal flowing into the channels 36, and as they are retracted from each other they increase the flow of coal to the channels.

Whereas the construction just described provides for an improved coal-distributing device which can be located lower in the firing opening and which improves the distribution of the coal feed to the rearward corners of the firebox, the elevated chutes 36 extending as they do into the firebox proper, and exposed as they are to the intense heat of the firebox are subject to more rapid deterioration than is the main body of the plate 24. Referring to Figures 5 through 10, a modification of the distributor plate mechanism is shown in which this difficulty is overcome by making the chutes 36 removable from the body of the distributor plate so that the chutes may be replaced independently of the main body portion.

Referring to Figure 5, the central or table portion 34 of the distributing mechanism 24 is shaped the same as shown in Figure 2, but as indicated along the line 70 a break is provided in the chutes 36 so that they now comprise two portions generally indicated at 71 and 72 (Figure 9). The portion 71 is integral with the body of the dis-

tributor plate and carries the downwardly projecting elongated lug 43 which cooperates as described in connection with Figure 2 with the supporting arms 41 extending forwardly from the blast chamber to removably support the distributor apparatus from the blast chamber.

The removable sections 72 of the chutes (Figures 7 and 9) have rearwardly projecting tongues 73 adapted to fit into corresponding grooves 73a in the webs 40 of the body of the distributor plate. The rearward ends of the tongues have upstanding lips 74 to hook behind the lugs 43. The tongues are so spaced by the grooves 73a as to come just inside the supporting arms 41 extending forwardly from the blast chamber so as not to interfere with these arms in their locking engagement with the lugs 43. The upstanding lips 74 and the lugs 43 have engaging surfaces which both slope forwardly, as shown in Figure 7. The tongue 73 and groove 73a serve to keep the chute sections 72 in proper alignment and the inclined contacting surfaces between the lugs 43 and the lips 74 serve to keep the two sections in tight abutting relationship along the line 70.

The forward ends of the chute sections 72 are prevented from tipping downwardly about the lugs 43 by contact between the underface 72a of the chute sections 72 and the top surface 40a of the webs 40.

Each section 72 thus maintained in locking engagement with respect to the integral sections 71 may be removed by raising its forward end upwardly to disengage the lip 74 from the lug 43, and then sliding the section 72 clear of the base portion of the plate 24. A new removable chute section 72 may be hooked in place by reversing the operation. This construction thus provides for the replacing of the chutes 36 independently of the body portion of the distributing apparatus.

As various embodiments might be made of this invention, and as various changes might be made in the construction herein described, all without departing from the scope of the invention, it is to be understood that all matter herein set forth or shown in the accompanying drawings is to be interpreted as illustrative and not in a limiting sense.

I claim:

1. In apparatus for distributing over a firebox through a firing opening in the back wall thereof of coal supplied thereto by conveying apparatus, in combination, a blast chamber adapted to be located within said firing opening and adjacent the bottom wall thereof and constructed to direct over the firebox a plurality of steam jets to distribute over the firebox coal falling into the paths of said steam jets, said steam jets being located in at least two different horizontal planes, and coal-guiding apparatus located within said firing opening forwardly of said blast chamber, and cooperating with said jets to guide the coal particles moving under the influence of the steam jets, said coal-guiding apparatus comprising a table portion having coal supporting and guiding surfaces for cooperating with the lower jets to distribute the coal over the central, front and side portions of said firebox, and two elongated chute portions having coal supporting and guiding surfaces elevated above either side of said table portion and curved toward the respective rearward corners of said firebox to cooperate with the upper steam jets to distribute coal over the rearward corners of said firebox;

said chute portions being removably supported by said table portion.

2. In apparatus for distributing over a firebox through a firing opening in the back wall thereof coal supplied thereto by conveying apparatus, in combination, a blast chamber adapted to be located within said firing opening and adjacent the bottom wall thereof and constructed to direct over the firebox a plurality of steam jets to distribute over the firebox coal falling into the paths of said steam jets, said steam jets being located in at least two different horizontal planes, and coal-guiding apparatus located within said firing opening forwardly of said blast chamber, and cooperating with said jets to guide the coal particles moving under the influence of the steam jets, said coal-guiding apparatus comprising a table portion having coal guiding and supporting surfaces for cooperating with the lower jets to distribute the coal over the central, front and side portions of said firebox, two elongated chute portions having coal guiding and supporting surfaces elevated above either side of said table portion and curved toward the respective rearward corners of said firebox to cooperate with the upper of said steam jets to distribute coal over the rearward corners of said firebox, and vertical diverging webs extending between said table portion and said chute portions to limit the sideward movement of the coal particles passing over said table portion.

3. In apparatus for distributing over a firebox through a firing opening in the back wall thereof coal supplied thereto by conveying apparatus, in combination, a blast chamber adapted to be located within said firing opening and adjacent the bottom wall thereof and constructed to direct over the firebox a plurality of steam jets to distribute over the firebox coal falling into the paths of said steam jets, said steam jets being located in at least two different horizontal planes, and coal-guiding apparatus located within said firing opening forwardly of said blast chamber, and cooperating with said jets to guide the coal particles moving under the influence of the steam jets, said coal-guiding apparatus comprising a table portion having coal guiding and supporting surfaces for cooperating with the lower jets to distribute the coal over the central, front and side portions of said firebox, two elongated chute portions having coal guiding and supporting surfaces elevated above either side of said table portion and curved toward the respective rearward corners of said firebox to cooperate with the upper steam jets to distribute coal over the rearward corners of said firebox, and adjustable means rearward of said blast chamber for controlling the flow of coal to said chute portions.

4. Coal distributing apparatus utilizing a steam blast for blowing coal over a firebed, consisting in the combination of a distributor plate having a substantially horizontal coal guiding and supporting surface over which coal flows under the influence of said steam blast, channels on either side of said surface through which coal passes under the influence of said blast to the side portions of the firebed, and elevated chutes having coal guiding and supporting surfaces located directly above and spaced from said first-mentioned channels for directing coal flowing under the influence of said steam blast to the rearward corners of said firebox.

5. Coal distributing apparatus utilizing a steam blast for blowing the coal over a firebed, consisting in the combination of a distributor

plate having a substantially horizontal coal guiding and supporting surface over which coal flows under the influence of said steam blast, channels on either side of said surface through which coal passes under the influence of said blast to the side portions of the firebed, elevated chutes having coal guiding and supporting surfaces located directly above and spaced from said first-mentioned channels for directing coal flowing under the influence of said steam blast to the rearward corners of said firebox, and approximately vertical webs extending up from the far sides of said channels to said chutes to support said chutes and limit the sideward travel of the coal.

6. Coal distributing apparatus adapted to be mounted in the lowermost portion of the hand-firing opening of a locomotive boiler backhead so as to form a minimum obstruction to said firing opening, said distributing apparatus comprising, in combination, a blast chamber adapted to emit blasts over said firebox in several different horizontal planes, one above the other, a coal distributing device having a central portion provided with a substantially horizontal coal guiding and supporting surface and adapted to cooperate in the distribution of coal with the lower of said steam blasts, diverging depressed channels on either side of said central portion for guiding the coal under the influence of said steam blast to the sides of said firebox, and elongated chutes located above and crossing said channels and having coal guiding and supporting surfaces for guiding the coal under the influence of the upper of said steam blasts, said chutes extending appreciably forward of said channels and central portion and being curved outwardly at their delivery ends.

7. Coal distributing apparatus adapted to be mounted in the lowermost area of the hand-firing opening of a locomotive so as to form a minimum obstruction to said firing opening, said distributing apparatus comprising, in combination, a coal guiding member having a central portion provided with a substantially horizontal coal guiding and supporting surface, and with diverging, depressed channels on either side of said central portion, and elongated coal supporting and guiding chutes located above and crossing said channels, said chutes extending appreciably forward of said channels and central portion and being curved outwardly at their delivery ends.

8. In coal distributing apparatus, in combination, a blast chamber adapted to emit a steam blast for blowing coal over a firebed, a distributor plate having a substantially horizontal coal guiding and supporting surface over which coal flows under the influence of said steam blast, channels on either side of said surface through which coal passes under the influence of said blast to the side portions of the firebed, elevated chutes having coal guiding and supporting surfaces located directly above and spaced from said first-mentioned channels for directing coal flowing under the influence of said steam blast to the rearward corners of said firebox, and means rearward of said blast chamber for regulating the presentation of coal selectively to said elevated chutes.

9. The combination with a firebox provided with a back wall having a firing opening, of coal distributing mechanism disposed in said opening, said mechanism including lower coal distributing means having a plurality of relatively extensive coal guiding and supporting surfaces constructed to handle the major portion of the coal sup-

plied to the firebox, and to guide it to the central and side portion and far corners of the firebox, said surfaces terminating within the confines of said opening and thereby being protected from the heat of the fire in said firebox by the walls of said firing opening, and upper coal distributing means having coal guiding and supporting surfaces elevated substantially above the lower means and extending into said firebox beyond said firing opening and thereby being exposed to the destructive heat of the fire in said firebox, said upper means being constructed to guide coal to the rear corners of said firebox, and at least that portion of said upper means extending into said firebox being detachable from the lower means, whereby it may be readily replaced when deteriorated by the heat from the fire in the firebox.

10. In a stoker for feeding coal to and distributing it over a firebox through a firing opening in the back wall thereof, a coal-distributing apparatus comprising the combination of means

for emitting two series of fluid-pressure jets, one series in a horizontal plane adjacent the bottom of said firing opening and the other series in another horizontal plane above the said bottom, a main distributor plate adapted to be centrally located in said firing opening adjacent the bottom thereof so that the lowermost of the series of jets will propel coal over the upper surface thereof, said upper surface having such formation as to direct said coal to the central, front and side portions only of the firebox, a pair of side-delivery chutes adapted to be mounted in the firing opening at the sides thereof above said main distributor plate, in such position that the 15 upper series of jets will propel coal therewith, the delivery ends of said chutes being elevated substantially above the main distributor plate and curved to direct coal flowing therethrough to the rear corners of said firebox, and means for 20 delivering coal to the rear ends of said plate and said chutes.

WILLIAM THOMPSON HANNA.
